UNITED STATES PATENT OFFICE.

JAMES T. ANDREW, OF MONTGOMERY, ALABAMA.

SAFETY DEVICE FOR RAILROAD-CARS.

No. 895,936.

Specification of Letters Patent.

Patented Aug. 11, 1908.

Application filed August 19, 1907, Serial No. 389,205. Renewed March 19, 1908. Serial No. 422,087.

To all whom it may concern:

Be it known that I, JAMES T. ANDREW, a citizen of the United States, residing at Montgomery, in the county of Montgomery and State of Alabama, have invented certain new and useful Improvements in Safety Devices for Railroad-Cars; and I do hereby declare the following to be a full, clear, and exact description of the invention, such as will enable others skilled in the art to which it appertains to make and use the same.

My invention relates to improvements in safety devices for railroad cars, and the object of my invention is to provide means whereby derailment of a train, with the injurious effects resulting therefrom, shall be rendered practically impossible, this application being an improvement upon my former patent No. 844,288, dated February 20, 1907, my former application Serial No. 349,727, dated December 27, 1906, and my former application Serial No. 362,975, dated March 18, 1907, and allowed April 16, 1907.

My invention is applicable not only to all railroad cars, but also to electric cars of all descriptions, and to locomotives.

With this object in view my invention consists in the construction and combination of parts as hereinafter more fully described and particularly pointed out in the claims.

Referring to the accompanying drawings forming a part of this application; Figure 1 represents a perspective view of a suitable truck showing my invention applied thereto, and also showing a part of the track. Fig. 2 represents an end view of the truck with my invention applied thereto, and showing the track in section. Fig. 3 represents a side view of a portion of my invention intended to be applied to the Westinghouse air brake apparatus now carried by railroad cars, and Fig. 4 is a plan view of the same. Fig. 5 is an end view, partly in section, of the device shown in Figs. 3 and 4, and Fig. 6 shows a modified form of device for accomplishing the same purpose.

Like letters refer to like parts in all the views.

A represents the wheels, B the axles, C the journal boxes, and D the equalizer of any suitable car truck. Underneath the framework of this truck I provide two bars E, and firmly secure the same thereto. From these

bars E I support the quarter wheels F in the manner and for the purpose fully disclosed in my pending application No. 362,975, above referred to. These quarter wheels F are supported on each side of the truck, as clearly shown in Fig. 2, and upon each axle B inside of the wheels I support two additional wheels G. These wheels G are rigidly secured to the axle and are preferably removable therefrom as are the regular wheels A of the truck, but, of course, I may form them integral with the axle, or for that matter may form them integral with the wheels A. These wheels G are provided with an inclined tread H, which tread is much steeper, or more inclined than the tread of the wheels A, for a purpose to be described hereinafter. The quarter wheels F are provided with suitable springs J, as shown, which serve to automatically return them to normal position whenever the said quarter wheels are displaced therefrom, and said quarter wheels are also provided with a tread K which is not so steep as the treads H, and is much broader than the same.

Referring to Figs. 3 to 6, L represents the usual air supply pipe of the Westinghouse air brake system, M a valve controlling the same provided with the levers N, which levers have the connections O with the rods P carrying the pivoted levers Q adapted to contact with the safety wheels G, when the car is derailed, all as shown in Figs. 3, 4, and 5. The rods P are suitably hung from the bottom of the car by the brackets R, as shown.

In the modification shown in Fig. 6, the levers N are provided with connections S joining the same to the levers T, suitably hung from the bottom of the car, as shown, and these levers T are in turn provided with the connections U joining the same with the tripping collars V. These tripping collars are split, as shown, and one of the same encircles each axle.

The operation of my device, is as follows:— Suppose the wheels A leave the track, say to the left, as seen in Fig. 2. As soon as the flange of the wheel A, on the left of said figure, rises on top of the rail, the truck will be tilted, and one of the levers Q, shown in Fig. 5, will contact with one of the wheels G, or else one of the collars V will bind against one of the axles of said truck. In either case, the

valve M of the air brake system will be operated, and the air brakes instantly applied to the train. As the momentum of the car carries the wheel A, that has been lifted, off the 5 rail, of course, the wheel A on the opposite side of the truck will be likewise carried off of the rail, suppose to the left, as seen in Fig. 2; and when this happens the quarter wheel K on the right of Fig. 2 will be thrown on top of 10 the rail, and the safety wheel G on the left of Fig. 2 will likewise contact with the other rail.

It will be observed that, as above stated, the treads of the wheels G are more inclined 15 than the treads of the wheels A, and therefore, as soon as the wheel G, on the left of Fig. 2 contacts with the rail, it will tend to slide off and to throw the train to the right. This 20 will cause an action somewhat like a glancing blow. That is to say, in the case supposed, when the whole train is urged by its momentum to the left, the glancing blow, so to speak, of the wheel G, will tend to deflect the truck again to the right and thereby tend to 25 keep the truck upon the track. This action is greatly aided by the broad tread of the quarter wheel K, and also by the peculiar action and function of said quarter wheel. That 30 is to say, as soon as the safety wheel G contacts with the rail on the left of Fig. 2, the quarter wheel K contacts with the rail on the right of Fig. 2, and since the wheel G on the left is capable of turning, that side of the car and truck is free to roll, while the quarter 35 wheel must slide. The combined action, therefore, of the said wheel G and of the said quarter wheel, serves to powerfully counteract the direction in which the train is being derailed. In other words, that quarter wheel 40 K which happens to contact with the rail, serves as a kind of pivot, on which the derailed truck will turn, and the safety wheel G serves as a kind of a roller to guide the truck around the pivoting quarter wheel, and 45 thereby change the direction in which the derailment is occurring. This whole action is greatly aided by the fact that the center of gravity of the stem is in a plane passing somewhere between the wheels A of the 50 truck, and therefore it acts with a leverage around the pivoting quarter wheel, thus tending powerfully to throw the train back upon the track.

In actual practice, in over fifty trials, where 55 full sized cars drawn by a full sized engine on a standard track and running at speeds varying from eight to fifty miles an hour were used, I have abundantly demonstrated that I can derail a train by this device and stop 60 the same without destroying the cars or their equipment. In other words, I have used the same cars, and substantially the same safety device in at least fifty trials, all of which demonstrated the principles above set

forth, to be sound in both theory and practice. 65

Of course, I do not desire to be limited to the exact details of construction herein disclosed, for the same may be varied by those skilled in the art without departing from the 70 spirit of my invention.

Having now described my invention, what I claim is:—

1. In a safety appliance for cars and locomotives, the combination of a truck provided 75 with the usual wheels, means carried thereby for automatically applying the brakes in case of accident, quarter wheels carried by said truck on the outside of said usual wheels, and safety wheels on the inside of the same, 80 whereby upon derailment the brakes are at once applied, a sliding action is induced by said quarter wheels, and a rolling action by said safety wheels, substantially as described. 85

2. In a safety appliance for cars and locomotives, the combination of a truck carrying the ordinary wheels and axles, a quarter wheel carried by said truck outside of each of 90 said wheels, a safety wheel carried by said axle inside each of said wheels, each of said quarter wheels being provided with a tread broader than said ordinary wheels, and each of said safety wheels being provided with a tread steeper, or more inclined, than the 95 treads of said ordinary wheels, and an automatic means adapted to apply the brakes as soon as one of said ordinary wheels leave the track, substantially as described.

3. In a safety appliance for cars and locomotives, the combination of a truck carrying the ordinary wheels and axles, a quarter wheel carried by said truck outside of each of 100 said wheels, a safety wheel carried by said axle inside each of said wheels, each of said 105 quarter wheels being provided with a tread broader than said ordinary wheels, and each of said safety wheels being provided with a tread steeper, or more inclined, than the 110 treads of said ordinary wheels, and an automatic means, consisting of a valve provided with levers N, of levers Q of brackets R, suspended from the car body, supporting said levers Q, and connections between said levers N and Q, adapted to apply the brakes as soon 115 as one of said ordinary wheels leaves the track, substantially as described.

4. In a safety appliance for cars and locomotives, the combination of a truck provided 120 with the wheels A, the axles B, the journal boxes C, the equalizer D, the supporting bars E, the quarter wheels F supported from said bars E, outside of said wheels A, the safety wheels G supported on the axles B inside 125 said wheels A, and provided with the treads H, steeper or more inclined than the treads of the wheels A, the train pipe L, valve M, having the levers N, rods P, connections O,

and levers Q adapted to be operated by said safety wheels, whereby when a wheel A leaves the track, one or more quarter wheels will slide along one rail, and one or more safety wheels will roll along the other rail, and thereby tend to throw the train back upon the track, substantially as described.

In testimony whereof, I affix my signature, in presence of two witnesses.

JAMES T. ANDREW.
